MEANS FOR CONNECTING RAILWAY AND LIKE RAILS

Ludwig Martin, Wuppertal-Elberfeld, Germany, assignor
to Dusseldorfer Eisenhutten Gesellschaft, Ratingen,
near Dusseldorf, Germany

Application November 16, 1954, Serial No. 469,250

Claims priority, application Germany November 17, 1953

9 Claims. (Cl. 238—173)

This invention relates to a rail joint having one or more flat or leaf springs arranged below the joint, the springs extending in the direction of the rails and being supported at their ends in two supports running transversely of the rail and fixed to the rail adjacent the joint. In the known rail joints of this kind, the fixing means for the supports for the springs to the foot of the rail is unsatisfactory because it is continually subject to the influence of the movement of the flat springs. The supports then became loose and began to shift on the rail foot.

In the rail joint according to the invention this difficulty is overcome and the support is fixed to the foot of the rail in such a manner that it cannot work loose. According to the invention, the supports for the leaf spring or springs consist of two separate U-shaped members, of which the ends of the arms are formed as screw-threaded bolts, and means for fixing the U-shaped members to the rail foot consists of two clamping plates of which one is fixed to the arms of the U-shaped member and the other is placed on the rail foot, which engages in the U-shaped member, and is clamped by means of a nut, by tightening which the springs are first tensioned and, after the lower clamping plate abuts against the foot of the rail, a secure connection is made.

The connection between the ends of the U-shaped member and the rail foot which is made in this manner is not only under the pre-tension of the springs, but also is under an additional clamping force which is independent of this pre-tension. The connection is, therefore, independent of the behaviour of the springs. This independence exists at each of the two U-shaped members which underlie the ends of the springs.

Another important advantage of the rail connection of the invention is that the tensioning of the springs takes place simultaneously with the making of the connection between the rail foot and the U-shaped member.

According to further features of the invention, the leaf springs arranged in the U-shaped clamping members are provided at their ends which project from the U-shaped members with bent portions which act as stops and prevent displacement of the springs. There may also be arranged between the leaf springs and the foot of the rail a transverse plate having upper flanges which embrace the foot of the rail and lower flanges which embrace the springs. The plate together with two lugs on the fish plates between which it is interposed acts as a spacer for the U-shaped members. In order to maintain a fixed and unalterable spacing between the U-shaped members, the fish plates are short and are held to the rails only by a single bolt passing through the centre of the joint. The fish plates are so formed that only the ends of their longitudinal edges abut against the head and foot of the rails.

The invention is illustrated, by way of example, in the accompanying drawing, in which:

Figs. 1 and 2 show the rail connection in side elevation and plan respectively, and

2

Figs. 3 and 4 are sections on the lines III—III and IV—IV of Fig. 1 respectively.

Referring to the drawing, the rails 3, 4 which rest on the sleepers 1, 2 and are fixed to them in known manner are supported in the region of the joint 5 by two superimposed bent leaf-springs 6, 7. The ends of these springs, which at first are not pre-tensioned, rest on two separate and independent U-shaped members 8 which run transversely of the longitudinal direction of the rails and are to be clamped to the rail foot 9. For this purpose, the ends of the arms of the members 8 are in the form of threaded bolts 10. A lower clamping plate 11 is fixed to or supported on each arm of the member 8. After the rail foot 9 has been introduced into the member 8, a second clamping plate 12 is placed on the ends of the arms of the U-shaped members 8 and over the rail foot and the member 8 is then clamped by tightening the nuts 13. The springs 6, 7 are thereby tensioned until the lower clamping plate 11 bears against the rail foot 9.

After this, the final tightening or clamping of the screw connection takes place. The upper clamping plate 12 is thereby clamped against the rail foot 9 and the lower clamping plate 11. The final connection therefor is subject to the pre-tension of the springs 6, 7 and to an additional clamping force applied after the pretensioning of the springs.

The flat springs 7 project laterally from the U-shaped members 8 and their ends are bent downwardly. This provides sufficient play between the bent portions and the U-shaped members 8 to allow for lengthening of the rails.

Between the upper flat spring 6 and the rail foot 9 is inserted a plate 14 which runs transversely of the longitudinal direction of the rails and is provided with lateral guide flanges 15, 16. The guide flanges 15 embrace the rail foot and the guide flanges 16 embrace the spring plates 6, 7. They, therefore, prevent relative lateral shifting between the rails and the springs.

In order to prevent shifting of the plate 14 in the longitudinal direction of the rails, the fish plates 17 connecting the two rails 3 and 4 are each provided with two extending lugs 18, 19. The lugs 18 and 19 engage around the foot of the rail and secure the plate 14 laterally between them. The two lugs 18, 19 and the plate 14 thus act as spacers for the members 8.

The plate 14 is held particularly securely between the lugs 18, 19 of the members 17 and the spacing of the members 8 is well maintained, if the fish plates 17 are in the form of short plates which are fixed only by a single bolt 20 which passes through the middle of the rail joint. As distinguished from the known fish plates, the upper and lower edge surfaces of which are each wedge over their entire length against the head and foot of the rail, in the fish plates used in the invention the edges are wedged against the head and foot of the rails only at the ends 21 of the plates 17. The middle part 22 of the fish plates is not in contact with the head and foot of the rails. In this way the fish plates are held very securely and, therefore, the plate 14 is also securely held and the spacing by the lugs 18, 19 and the plate 14 is well maintained.

I claim:

1. Means for connecting railway and like rails, comprising a leaf-spring underlying the rails at the joint and extending in the longitudinal direction of the rails, a pair of U-shaped members in which each of the ends of the said spring are supported respectively, the arms of said U-shaped members being screw-threaded at the ends, a pair of clamping plates on each of the arms of said U-shaped members for engaging above and below a rail foot introduced between said arms, and a nut threaded

on each of said screw-threaded ends for clamping said rail foot between said clamping plates.

2. Means for connecting railway and like rails, comprising a leaf-spring underlying the rails at the joint, and extending in the longitudinal direction of the rails, a pair of U-shaped members in which each of the ends of said spring are supported respectively, said spring having downwardly bent portions projecting from said U-shaped members, the arms of said U-shaped members being screw-threaded at the ends, a pair of clamping plates on each of the arms of said U-shaped members for engaging above and below a rail foot introduced between said arms, and a nut threaded on each of said screw-threaded ends for clamping said rail foot between said clamping plates.

3. Means for connecting railway and like rails, comprising a leaf-spring underlying the rails at the joint and extending in the longitudinal direction of the rails, a pair of U-shaped members in which each of the ends of said spring are supported respectively, the arms of said U-shaped members being screw-threaded at the ends, an upper clamping plate and a lower clamping plate on each of the arms of said U-shaped members for engaging above and below rail foot introduced between said arms, a plate member disposed transversely of the rails between said spring and said rail foot and intermediate said U-shaped members, flanges on the ends of said plate member, said flanges embracing the sides of said rail foot and said spring, and nuts threaded on the screw-threaded ends of said arms.

4. Means for connecting railway and like rails, comprising a fish plate disposed on each side of said rails, a leaf-spring underlying said rails at the joint and extending in the longitudinal direction of the rails, a pair of U-shaped members in which each of the ends of said spring are supported respectively, the arms of said U-shaped members being screw-threaded at the ends, an upper clamping plate and a lower clamping plate on each of the arms of said U-shaped members for engaging above and below a rail foot introduced between said arms, and a nut threaded on each of said screw-threaded ends for clamping said rail foot between said clamping plates.

5. Means for connecting railway and like rails, comprising a fish plate disposed at each side of said rails, means fixing said fish plates to said rails, a leaf-spring underlying said rails at the joint and extending in the longitudinal direction of the rails, a pair of U-shaped mem-

bers in which each of the ends of said spring are supported respectively, the arms of said U-shaped members being screw-threaded at the ends, a pair of clamping plates on each of said arms for engaging above and below a rail foot introduced between said arms, a plate member disposed transversely of the rails between said spring and said rail foot and intermediate said U-shaped members, lugs on said fish plates engaging said transverse plate and said U-shaped members and nuts threaded on said ends of said U-shaped members.

6. Means for connecting railway and like rails as claimed in claim 5, said fish plates being recessed so as to engage the head and foot of the rails only at their ends.

7. Means for connecting railway and like rails as claimed in claim 5, said fish plates being clamped to said rails by a single bolt passing through the rail joint.

8. Means for connecting railway and like rails comprising a pair of fish plates, means clamping said fish plates

20 to adjacent ends of said rails, a leaf-spring underlying the rails and extending in the longitudinal direction of the rails, a pair of U-shaped clamps in which each of the ends of said spring are supported respectively, the arms of said U-shaped members being screw-threaded at the ends, 25 a pair of clamping plates for engaging below the foot of the rail fixed to said arms, and a pair of clamping plates for engaging above the foot of the rail displaceable on said arms, and nuts threaded on the ends of said arms.

9. Means for connecting railway and like rails comprising a pair of fish plates, a bolt connecting said fish plates to said rails, a leaf-spring underlying said rails and extending in the longitudinal direction of the rails, a pair of U-shaped members in which each of the ends of said spring are supported respectively, the arms of said U-shaped members being screw-threaded at the ends, a pair of clamping plates on each of said arms for engaging above and below a rail foot introduced between said arms, a plate member disposed transversely of the rails between said spring and said rail foot and intermediate said U-shaped members, flanges on the ends of said plate member, said flanges embracing the sides of said rail foot and said spring, lugs on said fish plates engaging between said transverse plate member and said U-shaped members, and nuts threaded on the ends of said U-shaped members.
